IGNITION SYSTEM

Wilbur L. Carlson, Rochester, N. Y., assignor to
 General Motors Corporation, Detroit, Mich., a
 corporation of Delaware

Application January 20, 1939, Serial No. 251,889

2 Claims. (Cl. 123—149)

This invention relates to ignition systems for internal combustion engines and more particularly to ignition systems for internal combustion engines which drive generators for producing voltages that are relatively high as compared with the voltages which prevail in automotive vehicles.

The voltages most frequently used for automotive vehicles are 6 volts, or sometimes 12 volts. No difficulties are encountered when using this 10 6 volt ignition coil or 12 volt coil; but when the voltage generated by the generator driven by the internal combustion engine exceeds 12 volts by a substantial amount, for example, if the voltage is 32 volts, the problem is much more difficult 15 because it is practically impossible to design a theoretically correct 32 volt ignition coil. If such a coil were designed, the number of primary turns would be so great that 1,000 volts or higher would be impressed across the breaker points and primary condenser. If this high voltage were allowed severe arcing would result. This would seriously interfere with the performance of the coil and burn up the breaker points. If a large enough condenser were used to eliminate arcing, 20 the natural electrical period of the primary circuit would be so slow that insufficient voltage would be generated in the secondary coil.

In the past the practice has been to use a 12 volt coil in a 32 volt system. A series resistance 30 is connected between the 12 volt coil and the 32 volt source in order to consume the difference in potential. When this is done the coil does not operate efficiently and furthermore trouble may be caused by early ignition. A comparatively high 35 voltage is generated in the primary circuit at the time the breaker points close thereby causing a spark to jump at the spark gap at the wrong time. The strength of this early ignition spark is directly proportional to the impressed voltage and the turn ratio of primary to secondary turns. 40 If an attempt is made to reduce the early ignition spark by reducing the turn ratio, poor performance will result due to lower secondary voltage at the time of contact opening, when the regular spark is required. In order to produce a satisfactory spark under all conditions of operation, it is necessary to wind the ignition coil with a 45 comparatively high turn ratio. But if a high turn ratio is to be used, some method must be used to reduce the amplitude of primary voltage at the 50 instant of application to the coil. More recently this condition has been met to a certain extent by the use of a specially designed choke coil connected in series with the primary coil. At the 55 instant the breaker points close, the battery volt-

age is subdivided between the series choke inductance and the inductance of the primary coil. However, most of the voltage is consumed by the series choke due to its much higher inductance. But when the primary current starts to build up, 5 the series choke becomes highly saturated magnetically and shifts practically all of the battery voltage over the primary coil of the ignition coil.

The object of the present invention is to provide a circuit whereby a 12 volt ignition coil may 10 be used efficiently and without any of the aforementioned difficulties with a system of generation at a higher voltage, such as 32 volts for example. In the disclosed embodiment of the present invention I accomplish this object by grounding one of the generator commutator bars and I connect the ignition coil primary and the ignition timer in circuit with this grounded brush.

I so relate the generator to the ignition timer controlling cam that, when the grounded commutator bar is under the positive generator brush, the ignition timer contacts will be in the act of closing, and so that, when the ignition timer contacts are opened, the grounded commutator bar will have moved toward the negative brush a distance which is less than the full movement required but which is a distance such that the average voltage acting on the ignition coil primary will be correct for a 12 volt coil, for example. In this way while the generator is impressing the 30 voltage as high as 32 volts, for example, upon its terminals, the voltage obtained from the generator for ignition purposes is a relatively lower voltage suitable for a properly designed ignition coil.

Further objects and advantages will be apparent from the following description, reference being had to the accompanying drawing wherein a preferred embodiment of one form of the present invention is clearly shown.

In the drawing:

Fig. 1 is a diagram which shows the completion of the ignition circuit through the timer contacts and the grounded commutator bar at the instant that the bar is under the positive generator brush.

Fig. 2 is a wiring diagram similar to Fig. 1 showing the interruption of the ignition primary circuit at the instant the grounded commutator bar has moved seven bar spaces away from the positive generator brush.

Fig. 3 is a chart of voltages illustrating the operation of the present invention.

Fig. 4 is a wiring diagram showing the com-

plete starting, generating and ignition systems, which is shown partially in Figs. 1 and 2.

I will now describe the complete engine starting, generating and ignition system with reference to Fig. 4. The engine E having a spark plug P drives, through a shaft 20, a generator G and an ignition timer T. Generator G is shown as a bi-pole machine. Its armature coils are not shown in Fig. 4, but it will be understood that they are connected in a conventional manner with a commutator having bars 22. One of these bars is grounded by a connection from the point 23 to ground. Generator G has a positive brush 24 and a negative brush 25. It has a shunt field winding 26 used for generator purposes and a series field winding 27 used only for engine starting purposes. The terminal brushes 24 and 25 of generator G are connected with a storage battery B through an automatic circuit breaker or cut-out relay R. Relay R comprises a pair of normally open contacts 30 and 31 which are closed by the action of an armature, not shown, attracted to the core of an electromagnet around which are placed a series magnet coil 32 and shunt magnet coil 33. When the generator voltage attains a certain value the excitation of the coil 33 will be sufficient to effect the attraction of the relay armature toward its magnet core and cause contact 30 to engage contact 31 thereby closing the circuit between the generator G and the battery B. When the voltage of the generator falls below a certain amount the voltage impressed by the battery on the circuit will effect the opening of the automatic circuit breaker R, thereby preventing discharge of battery current through the generator.

The starting of the engine is effected by the closing of a switch S comprising a movable contact 42 normally held out of engagement with contact 40 and 41 by a spring 43. When this switch is closed current will flow from the battery to the generator to a circuit including a series field winding 27, thereby causing the generator to function as a motor for cranking the engine.

The timer T controls the completion and interruption of the ignition primary circuit.

Referring now to Fig. 1, the ignition primary circuit includes the grounded commutator bar, the positive brush 24, the primary winding 60 of the ignition coil C, and timer circuit breaker lever 61 which carries a contact 52 engageable with a grounded contact 53. The contacts 52 and 53 are shunted by a condenser 54 which reduces sparking at the contacts. Timer T includes a timer cam 50 driven by the generator shaft 20. Cam 50 is so located upon shaft 20 with respect to the grounded commutator bar that, when grounded bar is under positive brush 24, ignition timer cam 70 will have moved clockwise as shown in the drawing, sufficiently to clear the circuit breaker lever whereby a spring 51a causes the lever 51 to move clockwise to bring its contact 52 into engagement with contact 53. In other words, the instant the grounded bar is under the positive brush 24 the ignition primary circuit will be closed through the contacts 52 and 53. Ignition timer cam 50 is so shaped that when the grounded bar has moved a predetermined distance clockwise from the positive brush 24 toward the negative brush 25, the cam 50 will engage circuit breaker lever 51 to separate contact 52 from contact 53, thereby interrupting the ignition primary circuit. The instant of interruption of this circuit a voltage is induced in the primary 75 and transformed to higher voltage in the second-

ary winding 62 of the ignition coil C. A sparking impulse is thereby induced which is conveyed by wire connected between the secondary 63 and the spark plug P of the engine thereby igniting the fuel mixture at the proper instant in the cycle of operation of the engine.

The predetermined distance through which the grounded commutator bar moves during the closing period of the ignition timer depends upon the relative voltages of the ignition coil and of the generator. I have found, for example, when using a 12 volt coil with a 32 volt generator, that satisfactory ignition voltage is obtained from the generator if, during the closing period of the ignition primary circuit, the grounded commutator bar moves away from the positive generator brush an angular distance equivalent to seven commutator bar spaces.

In the particular embodiment of the invention disclosed in this application, I have chosen a generator in which there are nine bar spaces between the positive and negative brushes. I have therefore numbered these bars 9', 1, 2, 3, 4, 5, 6, 7, 8, 9, beginning with numeral 9' for the bar under the positive brush 24, and 9 for the bar under the negative brush 25. The generator armature coils are designated by A and also designated by numerals 1 to 9 inclusive. The angular relations between the bars and coils are shown in the chart of Fig. 3. As the bars are 20° apart, the nine bar spaces make up the 180° or half circle between the positive brush 24 and the negative brush 25. For purposes of calculation, the coil angles are not the same as the bar angles. As these coils may be considered as being concentrated half way between the center lines of adjacent commutator bars it is apparent that, as shown in the bottom line of the figures of the chart, Fig. 3, the spacings of the armature coils with respect to the center line of the bar marked 9', are 10° , 30° , 50° , etc., up to 170° . In the chart, Fig. 3, curve 70 represents individual coil voltages. It is depicted as the portion of a sine wave. Curve 73 represents the summation of individual coil voltages from the negative of the positive brush. Curve 74 represents the average voltage acting on the ignition circuit.

Curves 70, 74 and 73 are plotted from the following calculations which are based on the following premises: As previously explained, it will be understood that both the positive and the negative brushes of the generator are insulated from each other and from the frame of the engine which together with the generator forms a unitary power plant. One of the commutator bars is grounded. There will, therefore, be a difference in potential between any one of the main brushes and the frame of the generator. One side of the ignition circuit is grounded to the frame of the generator and the other side of the ignition circuit is connected to one of the insulated main brushes (positive brush 24) as shown in the drawing.

The breaker points are timed to close at the instant when the grounded bar is under the main brush 24 which has one side of the ignition circuit connected to it. Therefore, at this instant, there will be zero volts impressed on the primary coil 60 of the ignition coil C. This is shown in Fig. 1. At a predetermined time later the grounded commutator bar has moved away from the main brush as shown in Fig. 2. Any instant after the grounded bar moves away from the main brush 24 there is a potential difference across the ignition circuit and current starts to flow. The 75

amplitude of the voltage impressed on the ignition circuit depends on how many bar spaces the grounded bar has taken from the main brush 24; in other words, upon the number of armature coils included between the main brush and the grounded bar. Assuming that the breaker points are timed by the cam 50 to open when there are seven armature coils included between the main brush and the grounded bar, the maximum instantaneous voltage on the ignition circuit will be equal to the sum of the voltages generated in each of the included armature coils. In order for this system to function properly, the average value of the voltage between zero and the maximum voltage at the time of break must be equal to the voltage rating of the ignition coil. That is, if a 12 volt ignition coil is used, then the average voltage impressed on the coil between the time the breaker points close and open must be 12 to 14 volts. Curve 14 of Fig. 3 shows that the average voltage is 14 volts at the time the grounded commutator brush has moved seven bar spaces away from the positive brush 24.

In order to simplify the calculation of the data from which curve 10, 14 and 13 were plotted it is assumed that sinusoidal voltages are generated in the individual coils of the generator armature. Also assuming that there are nine (9) coils included between positive and negative brushes, the angle of the center-line of each armature coil from the main brush will be as follows:

Electrical degrees between positive and negative brush = 180°

35 Angle between coils =

$$\frac{180^\circ}{9} = 20^\circ$$

Angle between positive brush and center-line of first coil = 10°

40 This is shown in Fig. 3.

The highest voltage generated in any individual armature coil occurs when it is in the position of coil #5, Fig. 3, that is, when the coil is 90 electrical degrees from the neutral point, or, in the center of the magnetic pole.

Let E = the maximum voltage generated in the coil 90° from neutral. Then the voltage in any of the other coils at the same instant is:

50 $e = E \sin \phi$

where

ϕ = the electrical angle of the center of the coil from neutral or zero degrees. See Fig. 3.

55 The voltage generated by each coil is calculated and shown in Table 1.

Table 1

60	Coil No.	Coil angle	Sin of angle	Coil voltage = $E \sin \phi$	e
1		10	0.1736	0.1736E	e_1
2		30	0.5000	0.5000E	e_2
3		50	0.7650	0.7650E	e_3
4		70	0.9397	0.9397E	e_4
5		90	1.0000	1.0000E	e_5
6		110	0.9397	0.9397E	e_6
7		130	0.7660	0.7660E	e_7
8		150	0.5000	0.5000E	e_8
9		170	0.1736	0.1736E	e_9

70 Let E_0 = the total voltage between brushes.

Then

$$E_0 = e_1 + e_2 + e_3 + e_4 + \dots + e_9 \quad (1)$$

75 or the sum of all the individual coil voltages.

By an inspection of Table 1 we get for the summation

$$E_0 = 2E(0.1736 + 0.5000 + 0.7660 + 0.9397) + E \quad (2)$$

$$E_0 = 4.758E + E = 5.758E \quad (3)$$

Assuming the total voltage E_0 across the brushes to be equal to 36 volts, we get the following by substituting 36 for E_0 in Equation 3

$$36 = 5.758E \quad (4)$$

Then

$$E = \frac{36}{5.758} = 6.25 \text{ volts} \quad (5)$$

Substituting this value (6.25) for E in Table 1 we get

Table 2

e_1	$1.736 \times 6.25 = 1.085$
e_2	$5.000 \times 6.25 = 3.125$
e_3	$7.660 \times 6.25 = 4.79$
e_4	$9.397 \times 6.25 = 5.8$
e_5	$1.0000 \times 6.25 = 6.25$
e_6	$9.397 \times 6.25 = 5.8$
e_7	$7.660 \times 6.25 = 4.79$
e_8	$5.000 \times 6.25 = 3.125$
e_9	$1.736 \times 6.25 = 1.085$
E_0	35.850 total

As the grounded commutator bar moves from the positive to the negative brush, the maximum instantaneous voltage across the ignition coil is first zero. One bar from neutral the voltage is 1.085 volts. Two bars from neutral the voltage is $(1.085 + 3.125) = 4.21$ and so on all the way around the commutator. Or in general

$$e_n = e_1 + e_2 + e_3 + \dots + e_9 \quad (6)$$

Where E = the maximum instantaneous voltage impressed on the ignition circuit, or the summation of any number of the individual armature coil voltages.

The following Table #3 shows the maximum instantaneous voltages E_1, E_2, E_3 , etc., from the positive to negative brushes.

Table 3

1	$E_1 = 1.085$
2	$E_2 = 4.210$
3	$E_3 = 9.000$
4	$E_4 = 14.800$
5	$E_5 = 21.050$
6	$E_6 = 26.850$
7	$E_7 = 31.640$
8	$E_8 = 34.765$
9	$E_9 = 35.850$

Since the maximum instantaneous voltage, shown on Table 3, varies from zero volts to the voltage E_9 as the grounded bar moves from the positive to the negative brush, the average value of the maximum instantaneous voltages must be taken as the effective ignition voltage.

That is, the average voltage at the time when the grounded bar moved one bar distance past the neutral point is

$$E_{a1} = \frac{E_0 + E_1}{2} = \frac{0 + 1.085}{2} = .5425 \text{ volts}$$

and two bars past the neutral point we get

$$E_{a2} = \frac{E_0 + E_1 + E_2}{3} = \frac{0 + 1.085 + 4.21}{3} = 1.765$$

and so on all the way around the commutator. Or in general

$$E_{an} = \frac{E_0 + E_1 + E_2 + E_3 + \dots + E_n}{n+1} \quad (7)$$

Table 4 shows values of E_0 from $E_a=0$, to $E_a=9$

Table 4

5	Number of bar from zero	Average voltages impressed on the ignition circuit
1	E_{a1}	.5425
2	E_{a2}	1.7650
3	E_{a3}	3.5740
4	E_{a4}	5.8220
10	E_{a5}	8.3720
5	E_{a6}	11.0066
6	E_{a7}	13.5880
7	E_{a8}	15.9430
8	E_{a9}	17.9371

15 Up until this time it was assumed that there was no armature reaction. According to the laws of armature reaction the magnetic field shifts in the direction of rotation when the machine generates, but shifts against the direction of rotation when motoring.

20 In the chart, Fig. 3, arrow 80 pointing toward the right designates clockwise rotation corresponding to the manner of rotation indicated with respect to the operation of the generator 25 as shown in Figs. 1 and 2. Curves 71 shows individual coil voltages when the generator is operating as a motor. It will be observed that the coil voltage has shifted to the left. Curve 72 represents individual coil voltages when the machine 30 is generating at normal speed. It will be observed that armature reaction has shifted the individual coil voltage toward the right. It is therefore apparent that the effect of armature reaction is to automatically meet the demands 35 for voltage under starting and running conditions. That is, the effect of armature reaction when starting, will tend to raise the average voltage impressed on the ignition coil primary 40 and thus compensate for the low starting voltage. It will be understood that the voltage 45 impressed on the ignition coil is low when starting on account of the drain on the battery due to the starting operation. Armature reaction will have the opposite effect upon the ignition circuit during generating since the average voltages will be lowered to compensate for high charging voltages.

50 Instead of employing a generator having insulated positive and negative brushes and grounded commutator bar, the same results could be obtained by using a generator having a grounded brush and having a commutator bar connected to an insulated collector ring from which current is taken from a brush and conveyed to the ignition coil winding 60.

55 The advantages of my new system are as follows: No series resistance is required because correct voltage is supplied to the coil. No series reactance is required because zero potential is impressed on the coils when the primary circuit is closed by the breaker points. The wiring of the system has been simplified, hence it may be constructed at lower cost and there will be less liability for trouble. The system gives improved 60 performance over a system in which an attempt is made to use a 12 volt coil in a 32 volt system because the coil is operating efficiently.

65 I will now discuss the limitations to the satisfactory operation of an ignition system constructed in accordance with the present invention.

70 This system will not operate satisfactorily with all combinations of numbers of generator poles and number of cylinders. The combinations 75 which are correct are those in which the number

of cylinders divided by the number of poles in the generator will give either a whole and even quotient as a result of the division or a fraction which has an even number as a denominator reduced to lowest terms:

5 $\frac{\text{Number of cylinders}}{\text{Number of poles}} = \text{even number}$

or

10 $\frac{\text{Number of cylinders}}{\text{Number of poles}} = \frac{1}{\text{even number}}$

Example of correct combination

$$\frac{1 \text{ (cylinder)}}{6 \text{ (poles)}} = \frac{1}{6}$$

Example of incorrect combination

$$\frac{4 \text{ (cylinders)}}{6 \text{ (poles)}} = \frac{2}{3}$$

20 In order for this system to give good performance the following conditions must be met.

The number of poles or the generator R. P. M. or the combination of both must be of a value that will allow the ignition coil to become saturated magnetically. In other words, the time in seconds required for the grounded bar to move from the positive to the negative brush must bear a certain relation to the electrical time constant of the primary circuit.

25 Since the value of the impressed voltage also determines the rate of saturation of the primary circuit, this must be taken into consideration.

The relation of instantaneous primary current, time and impressed voltage are shown in Equa- 30 tion #8.

$$i = \frac{E}{R} \left(1 - e^{-\frac{Rt}{L}}\right) \quad (8)$$

35 The constants of an ordinary 12 volt system are approximately as follows:

$$\begin{aligned} E &= 12 \text{ volts} \\ L &= .02 \text{ henries, inductance} \\ R &= 3.4 \text{ ohms} \end{aligned}$$

40 Assuming that we take

$$t = \frac{L}{R} \text{ seconds}$$

45 for the minimum saturation time and substituting these values in Equation 8 we get:

$$\begin{aligned} i &= \frac{12}{3.4} \left(1 - e^{-\frac{Rt}{L}}\right) \\ &= 3.53 \left(1 - \frac{1}{e}\right) \\ &= 3.53 \left(1 - \frac{1}{2.718}\right) \\ &= 3.53 \times .632 = 2.235 \text{ amperes} \end{aligned} \quad 55 \quad 60$$

55 This is the current that a standard 12 volt coil will take on 12 volts when

$$t = \frac{L}{R} \text{ seconds} \quad 65$$

Since $L = .02$ and $R = 3.4$ we have

$$\frac{L}{R} = \frac{.02}{3.4} = .00589 \text{ seconds}$$

70 From this it will be seen that if the maximum that the coil would draw at 12 volts on stall is

$$\frac{E}{R} = \frac{12}{3.4} = 3.53 \text{ amperes}$$

then the ampères at a saturation time of

$$t = \frac{L}{R} = \frac{.02}{3.4} = .00589 \text{ seconds}$$

5 will be 2.235 amperes, or $(2.235/3.53) \times 100 = 63.2\%$ of max.

$$\frac{E}{R} \text{ current}$$

10 The time (t) allowed for the coil to saturate, by a generator of any number of poles and at any speed is

$$t = \frac{60}{R \cdot P. M. \times p} \text{ seconds} \quad (9)$$

15 For example, if the generator has 6 poles and operates at 1800 R. P. M., then substituting these values in Equation 9 gives

$$t = \frac{60}{1800 \times 6} = .00556 \text{ seconds}$$

20 This shows that when the maximum voltage between brushes is 36 volts and the number of poles are (6) six, the maximum allowable speed will approximately be 1800 R. P. M. Or in general

$$t = \frac{L}{R} \text{, and } t = \frac{60}{R \cdot P. M. \times p} \quad (10)$$

then

$$\frac{L}{R} = \frac{60}{R \cdot P. M. \times p} \quad (11)$$

therefore

$$R. P. M. = \frac{60R}{Lp} \quad (12)$$

or

$$R. P. M. = \frac{60 \times 3.4}{.02 \times 6} = 1700$$

40 During the cranking of the engine the ignition circuit includes the following: Battery B, switch S, series field 21, primary winding 60 of coil C, timer T, ground to the commutator bar grounded at 23, armature of generator G, brush 25 and return to battery B.

45 While the form of embodiment of the present invention as herein disclosed constitutes a pre-

ferred form, it is to be understood that other forms might be adopted, all coming within the scope of the claims which follow.

What is claimed is as follows:

1. An ignition system for prime-mover dynamo power plants comprising, in combination, a direct current generator, an internal combustion engine driving the generator, an ignition coil designed to operate on lower voltage than the generator terminal voltage and having a secondary winding connected with the engine spark plug and primary winding connectible with the generator, a circuit including the primary winding and a varying number of generator armature coils, and an engine-driven ignition timer circuit breaker 10 for making the ignition primary circuit when there are zero generator armature coils included in the circuit and for breaking the ignition primary circuit when there are a predetermined number of generator armature coils included in 20 the circuit (less than the full number of armature coils between generator terminal brushes), the predetermined number of armature coils being such that the average voltage impressed upon the ignition coil is approximately equal to the 25 rated voltage of the ignition coil.

2. An ignition system according to claim 1 in which the generator is provided with a grounded commutator bar, in which one end of the ignition coil primary is connected to a generator terminal brush, in which the other end of the ignition coil primary is connected to the ignition timer circuit breaker which is grounded, and in which the engine driven timer cam is so constructed and related to the generator that the circuit breaker 30 completes the ignition coil primary circuit when the grounded commutator bar is under the said terminal brush of the generator and that the circuit breaker interrupts the ignition coil primary circuit when the grounded bar has moved a 35 predetermined angular distance away from the said terminal brush of the generator, the predetermined distance being such that the average voltage impressed upon the ignition coil is approximately equal to the rated voltage of the 40 ignition coil.

WILBUR L. CARLSON.
